UNITED STATES PATENT OFFICE.

GEORGE M. LIVESAY, OF ASHLEY, ILLINOIS.

ELECTRIC LOCK.

Application filed September 18, 1922. Serial No. 588,980.

To all whom it may concern:

Be it known that I, GEORGE M. LIVESAY, citizen of the United States, residing at Ashley, in the county of Washington and

5 State of Illinois, have invented certain new and useful Improvements in Electric Locks, of which the following is a specification.

The present invention relates to electric locks as applied to the ignition system for 10 internal combustion engines, and more particularly to locks of this character for use on automobiles.

The object of the invention is to provide 15 a key for opening and closing the circuits to the engine cylinders and to arrange the wiring of the different circuits in such a manner that the insertion of a particular key and turning of the same will close the gaps formed in each circuit preliminary to starting 20 the engine and that the removal of the key will cause a break to be formed in each of the ignition circuits making it impossible to start the engine without this key in position.

25 Another object of the invention is to arrange the primary and secondary windings of the spark coil, so that a break also is formed therein, which break is bridged upon the insertion and turning of the key, 30 in this manner providing a double safety against the starting of the machine by any unauthorized person.

By arranging the wiring in the key box in different manner, different keys will have to 35 be used for different engines and by arranging the conductors in the keys in different directions, still greater variation in the construction of the locks and keys may be obtained.

40 One embodiment of the invention is illustrated in the accompanying drawings and,

Fig. 1 represents a perspective view of the wiring in the insulating block of the lock, the insulation material having been shown 45 as transparent for the sake of clearness;

Fig. 2 is a horizontal section of the lock;

Fig. 3 is a vertical section taken along line 3—3 of Fig. 2;

Fig. 4 is a longitudinal section along line 50 4—4 of Fig. 2;

Fig. 5 is an axial section of a key;

Fig. 6 is a perspective view of an oscillating contacting member of a lock;

Fig. 7 is a diagrammatic view of the primary and secondary windings of the spark coil;

Fig. 8 is a fragmentary perspective view of a dash board of an automobile with the electric lock attached;

Fig. 9 is a perspective view of a cover 60 plate for the box containing the electric lock, and

Fig. 10 is a similar view partly in section of the box itself.

In the drawings reference numeral 10 represents 65 a metal casing of rectangular shape having a cover plate 11 secured in front thereof by means of screws as at 12 see Figure 9.

Within this casing fits closely a block of 70 insulating material such as bakelite. This block is preferably divided along a medial line to form an upper half 13 and a lower half 14, which together entirely fill the casing, so as to be flush with the top thereof. 75

Centrally in this block is formed a chamber 15 running the entire length of the block and situated partly in the lower half 14 thereof and partly in the upper half 13. Adjacent to one end of said chamber is provided 80 a keyhole 16 in plate 11 of the casing 10. The end plate of the casing is provided with two or more ears 17 having apertures 18 for attaching the casing to the dashboard 65 of an automobile and bolts or screws 19 85 running through the top and bottom of the casing engaging in corresponding openings in the block 13, 14. The keyhole 16 has an upwardly directed slot 9 suitable for guiding the bits 20 arranged on one side of the 90 stem 21 of the key. The end of the key has a recess 22 adapted to engage with the stud 23 provided in the inner end of the casing 10 at the bottom of the chamber 15. This stud is intended for guiding the key when 95

the same is turned in the chamber and adjacent to each bit 20, with the key inserted in the chamber, is furnished a transverse recess 24 see Figure 3 to permit the turning of the key. The key is provided with a bow or 100 handle 25 at its outer end and in the casing is carried a sliding latch 26 actuated by a spring 27; the function of this latch being to retain the key in its turned position as indicated in Figs. 3 and 4, when the latch 105 26 engages the notch 28 on the under side of the key. This prevents the key from turning loose, when in its operative position, while the engine is running. The turning of the key one quarter turn until the bits 110 register with the slot 19 will immediately cut off the current and stop the engine.

Referring particularly to Fig. 5 short pieces of wire 30 run diametrically across the stem 21 of the key and through the bits 20. These wires are intended to bridge the gaps formed in the conductors of the circuits and for a six cylinder engine, there are preferably three bits 20 as shown in this figure, each bit containing two wires, which will consequently bridge the gaps for the circuits for two of the cylinders. The contacting ends 31 of these wires may run out to the sides, ends, tops or bottoms of the bits for the purpose of varying the construction of the keys and change combination of the locks.

Referring particularly to Figs. 1, 2 and 3 which illustrate the wiring diagram of this lock, the terminals 32, arranged in two rows of three terminals each, are shown on one side of the casing, each terminal connecting with the distributors and individual terminals in the wiring for each cylinder of the engine. On the opposite side of the lock other terminals 34 are furnished for wirings 35, also arranged in two rows of three each with individual wire for each cylinder. In the diagram shown in these figures short conductors 36 and 37 lead from their respective terminals on both sides toward the chamber and terminate in the wall opposite the corresponding contact points in the stem and bits of the key. In these diagrams the terminals on the distributor side of the casing are all denoted by letters A to F inclusive, and the terminals on the engine side of the casing are denoted by letters *a* to *f*. The connections are laid in such a manner that terminal A connects with terminal *a*, terminal B with *b*, C with *c* and so on. It will thus be seen that with the key turned round in the position indicated in this figure, the wiring on each side of the box will be connected in proper order.

The spark coil 53, which is best shown in Figs. 3 and 4 and diagrammatically in Fig. 7 consists of a primary winding 40 and a secondary winding 41 both being properly grounded. In the conductor 42, 42^b of the primary winding a break is formed as at 43 and this break is actuated by a so-called "cut-out." One end 42^a of the conductor 42 leads to the contact plate 45, see Figs. 3 and 7 which has preferably a contact point 44 of rare metal such as platinum. The other end 42^b of the conductor 42 is likewise secured to a plate 46, which carries a spring 47 being firmly attached to block 13 and having a pad 48 at its free end located oppositely to the contact point 44, the spring 47 tending to hold the pad 48 away from the contact point, thereby forming the "cut-out." At 49 is fulcrumed, in the upper half 13 of the block, an oscillating member 50 preferably made of insulating material such as bakelite. The lower end of this oscillat-

ing member is positioned in the path of one of the bits 20, preferably the middle one, and a steel spring 51 is rigidly attached to the upper end of the oscillating member and extends upwardly behind the pad 48 of the "cut-out." In order to accommodate this "cut-out" and the oscillating member, a recess 52 is provided in the upper half 13 of the block permitting the swinging to and fro of the oscillating member. With the parts in the position indicated in Figs. 2 and 3, when the bit 20 of the key has been turned down, the oscillating member 50 is swung outwardly causing the spring 51 to push the "cut-off" 47 and 48 in the right-hand direction, thereby closing the contacts and completing the circuit in the break 43 of the spark coil.

It will now be seen that individual spark plugs for the cylinders of the engine will be operated in proper order and the engine may be started.

By inserting pins in the blocks 13 and 14, which project into the recess for the bits, and furnishing corresponding slots in the latter, still further variation in the shape and construction of the keys may be obtained. In this manner assuring against tampering with the machinery and attempting to start it with a key, that will not fit the lock.

In Fig. 10 is shown the box or casing 10 in which the insulating blocks 13 and 14 containing the principal details of the lock are assembled. At 62 are shown longitudinal slots in the box to accommodate the wiring and terminals 32 and 34 respectively and to make the assembling easy. At 63 is shown a series of apertures provided for the conductors running to battery, ground and timer and at 64 are shown other apertures or screw holes for the screws 19 with which the insulating blocks 13 and 14 are secured in the casing 10.

The end plate 11 in Fig. 9 is shown with the lugs 17 for attaching the entire lock to the dash board 65 of the automobile. At 66 is shown an aperture of a supporting screw for the coil and a similar aperture 67 is provided in the opposite end of the box or casing 10 for the same purpose.

Instead of placing the wiring in the key in one transverse plane thereof as seen in Fig. 5, the wires may be laid in the key in two planes at right angles to each other. In other words each wire is bent so that its angles are spaced 90° apart in the outer face of the key.

The coil is positioned in such a manner in the upper insulating block 13, so that it may be easily removed provided it is found necessary to replace the same.

Having thus described the invention, what is claimed as new is:

1. A lock for electric ignition circuits

comprising a block of insulating material, a spark coil enclosed therein and provided with a "cut out" element, said block having a chamber, the conductors of said circuits terminating in the wall of the chamber forming a gap in each circuit, a switch member of insulating material mounted to turn in said chamber, wiring in said switch member adapted to bridge the respective gaps with the member in the "turned on" position, the latter simultaneously closing said "cut out."

2. A lock for electric ignition circuits comprising a block of insulating material, a spark coil enclosed therein and provided with a "cut out" element, said block having a chamber, the conductors of said circuits terminating in the wall of the chamber forming a gap in each circuit, a switch member of insulating material mounted to turn in said chamber, wiring in said switch member adapted to bridge the respective gaps with the member in the "turned on" position, the latter simultaneously closing said "cut out", said switch member being constructed as a removable key.

3. A lock for electric ignition circuits comprising a block of insulating material, a spark coil enclosed therein and provided with a "cut out" element, said block having a chamber, the conductors of said circuits terminating in the wall of the chamber forming a gap in each circuit, a switch member of insulating material mounted to turn in said chamber, wiring in said switch member adapted to bridge the respective gaps with the member in the "turned on" position, the latter simultaneously closing said "cut out", said switch member being constructed as a removable key having a plurality of bits, said wiring crossing the stem of the key with ends exposed respectively in said bits and the opposite side face of the stem in order to register with the respective conductors.

4. A lock for electric ignition circuits comprising a block of insulating material, a spark coil enclosed therein and provided with a "cut out" element, said block having a chamber, the conductors of said circuits terminating in the wall of the chamber forming a gap in each circuit, a switch member of insulating material mounted to turn in said chamber, wiring in said switch member adapted to bridge the respective gaps with the member in the "turned on" position, the latter simultaneously closing said "cut out" said switch member being constructed as a removable key; a casing enclosing said block having a key hole opposite said chamber and a latch in said casing adapted to retain said key in position.

5. A lock for electric ignition circuits comprising a block of insulating material,

a spark coil enclosed therein and provided with a "cut out" element, said block having a chamber, the conductors of said circuits terminating in the wall of the chamber forming a gap in each circuit, a switch member of insulating material mounted to turn in said chamber, wiring in said switch member adapted to bridge the respective gaps with the member in the "turned on" position, the latter simultaneously closing said "cut out", said switch member being constructed as a removable key, having a plurality of bits, said spark coil being provided with primary and secondary windings, a conductor for said primary winding having a break, a contact point for each end of the break, one of said contact points forming the "cut out", standing normally open and an oscillating member adjacent said "cut out" and adapted to be actuated by one of said bits for closing the "cut out".

6. A lock for electric ignition circuits comprising a block of insulating material, a spark coil enclosed therein and provided with a "cut out" element, said block having a chamber, the conductors of said circuits terminating in the wall of the chamber forming a gap in each circuit, a switch member of insulating material mounted to turn in said chamber, wiring in said switch member adapted to bridge the respective gaps with the member in the "turned on" position, the latter simultaneously closing said "cut out," said switch member being constructed as a removable key having a plurality of bits, said wiring crossing the stem of the key with ends exposed respectively in said bits and the opposite side face of the stem in order to register with the respective conductors; said spark coil being provided with primary and secondary windings, a conductor for said primary winding having a break, a contact point for each end of the break, one of said contact points forming the "cut out" standing normally open and an oscillating member adjacent said "cut out" and adapted to be actuated by one of said bits for closing the "cut out."

7. A lock for electric ignition circuits comprising a lock of insulating material, a spark coil enclosed therein and provided with a "cut out" element, said block having a chamber, the conductors of said circuits terminating in the wall of the chamber forming a gap in each circuit, a switch member of insulating material mounted to turn in said chamber, wiring in said switch member adapted to bridge the respective gaps with the member in the "turned on" position, the latter simultaneously closing said "cut out," said switch member being constructed as a removable key, having a plurality of bits, said wiring crossing the stem of the key with ends exposed respectively in said bits

and the opposite side face of the stem in order to register with the respective conductors; said spark coil being provided with primary and secondary windings, a conductor for said primary winding having a break, a contact point for each end of the break, one of said contact points forming the "cut out" standing normally open and an oscillating member adjacent said "cut out" and adapted to be actuated by one of said bits for closing the "cut out"; a casing enclosing said block having a key hole opposite said chamber and a latch in said casing adapted to retain said key in position.

8. A lock for electric ignition circuits comprising a block of insulating material and provided with a chamber, a spark coil provided with a "cut-out" element, the conductors of said circuits terminating in the wall of the chamber forming a gap in each circuit, and a switch member mounted to turn in said chamber and adapted to bridge the respective gaps, with said switch member in "turned on" position, said switch member simultaneously closing said "cut-out."

In testimony whereof I affix my signature.

DR. GEORGE M. LIVESAY. [L.S.]
